[57] **CLAIM**

The ornamental design for a magazine display rack, as
shown and described.

DESCRIPTION

FIG. 1 is a perspective view of a magazine display rack
showing my new design;

FIG. 2 is a front elevational view thereof;

FIG. 3 is a left side elevational view thereof;

FIG. 4 is a right side elevational view thereof; and

FIG. 5 is a top plan view thereof.

The rear of the rack is conventional in configuration.

Fig. 1.

Fig. 2.

Fig. 4.

Fig. 5.
